UNITED STATES PATENT OFFICE.

GABRIEL CARLSON, OF SPRINGFIELD, MASSACHUSETTS, ASSIGNOR TO THE CONFECTIONERS' MACHINERY AND MANUFACTURING COMPANY, OF SAME PLACE.

DEPOSITING-MACHINE FOR CONFECTIONERY.

SPECIFICATION forming part of Letters Patent No. 661,008, dated October 30, 1900.

Application filed July 12, 1900. Serial No. 28,350. (No model.)

To all whom it may concern:

Be it known that I, GABRIEL CARLSON, a citizen of the United States, residing at Springfield, in the county of Hampden and State of Massachusetts, have invented new and useful Improvements in Depositing-Machines for Confectionery, of which the following is a specification.

This invention relates to depositing-machines for confectionery mixtures; and one object of the invention is to construct a machine of this class in which provision is made for depositing the mixture in more than one row of molds at the same time and in which improved means for charging and discharging the cylinders from which the molds are filled are provided.

A further object of the invention is to improve the mechanism whereby the speed of operation of the machine as a whole may be varied and also in improvements in the mechanism whereby the quantity of material which may be taken into one of the mold-charging cylinders may be varied, all as fully set forth in the following specification and summarized in the claims appended thereto.

In the drawings forming part of this specification, Figure 1 is a side elevation of the depositing-machine embodying my invention. Fig. 2 is a front elevation of the same. Fig. 3 is a detailed view of one of the cylinders. Fig. 4 is a plan view of several of the cylinders, one being in section. Fig. 5 is a detailed view of the ratchet motion. Fig. 6 is a sectional elevation of a modified construction of the cylinders. Fig. 7 is a perspective view, partly in section, of said modified construction.

In machines of this class trays filled with some material, such as powdered starch, have mold-forms printed therein in equidistant rows, which trays are passed with a step-by-step movement under rows of discharge-openings with which the rows of molds register, and the confectionery mixture is by suitable mechanism forced through said openings in predetermined quantities, said mixture being in a liquid or semiliquid state. Heretofore it has been the practice to provide but one outlet from each of the mold-charging cylinders.

The invention forming the subject of this application provides for the discharge of the material into two or more molds at the same time.

In carrying out this invention, in a suitable frame *a* there is mounted a chain or other flexible conveyer *b* on two shafts *c* and *d*, hung in bearings in the opposite end of the frame. This chain is adapted to support and convey through the machine with a step-by-step movement the trays *e*, suitable guides *f* being erected to keep said trays on their true course. The referred-to step-by-step movement of the conveyer *b* is imparted thereto by a ratchet mechanism. (Shown more particularly in Figs. 1, 2, and 5, and which will be described later on.) The movement of this ratchet device, as well as the movements of the other parts of the machine, is imparted thereto by a shaft *g*, which in turn derives its motion from the driving-shaft *h*. About midway between the two ends of the frame *a* is located, extending transversely of the machine, a tank *i* is placed the confectionery mixture. Along the front of this tank, near the bottom edge thereof, a row of cylinders *j* are supported in a cylinder-bar *k*, which is secured removably to said tank. Said cylinders *j* are rotatably fitted into sockets bored in the cylinder-bar and secured therein by means of a stem *l* on the cylinder, which projects down through the bottom of the cylinder-bar and is fitted with a suitable nut, whereby the cylinder is retained in its position. Opposite each cylinder a hole *m* is bored through the cylinder-bar, which connects with a long narrow slot *n*, which extends across the face of the tank and is connected with the interior thereof. The bottom of each cylinder has bored therethrough a number of outlets *o*. In the drawings four are shown, though this number is purely arbitrary. Through the side wall of the cylinders, at the bottom thereof, there is bored an induction-port *p* of substantially the same area as the hole *m* through the cylinder-bar *k*. Through the bottom of the socket in which the cylinder rests are bored other holes *q* of the same diameter and number as the holes *o* through the bottom of the cylinder.

These holes q and o are so arranged relatively one to the other that when the induction-port p registers with the hole m then the holes q in the bottom of the cylinder-bar will be found located out of registering position with the holes o . A crank-arm r is provided for each of the cylinders j . This crank-arm is adapted to be swung to rotate the cylinders within their sockets, to the end that when the arm r is in the position shown in Fig. 4, for instance, the induction-port p of the cylinders will register with the holes m , which are in constant communication with the delivery-slot n of the tank, and, as stated, when the cylinder is in this position the holes q and o will be found to be out of registering position, and the piston s , through suitable mechanism to be described, will at about this point begin its upstroke. At the end of the upstroke of the piston the cylinder j is oscillated on its axis by means of the arm r to an extent sufficient to close the induction-port p and to bring into registering position the holes q and o . At this point the piston begins its downward movement to eject the contents of the cylinder from the latter through the four outlets o , which at this time lie directly over the holes q . Meanwhile the trays e have been fed along by the ratchet-motion to bring a mold-form (indicated in Figs. 3 and 6 by t) under each of the holes q . This piston at this point descends, ejecting the mixture contained in the cylinder into the mold-form beneath, and the piston then begins its return upward movement an instant before the cylinders are operated back to the position shown in Fig. 4, whereby any of the mixture remaining at the mouth of said opening will be drawn back into the cylinder before the rotation of the latter covers the holes q . By this means no drops of the sticky mixture are permitted to remain on the under side of the cylinder-bar k . The means whereby the oscillatory movement of the cylinders is imparted thereto are shown most plainly in Figs. 1 and 2.

On the shaft g is a gear u , which is connected, through an intermediate gear v , with one of a series of gears x , having different diameters, which are rigidly secured on the shaft h , the latter being rotated by a driving-pulley y . Positive movements are thus imparted to the shaft g , and, by means to be described, through the medium of the gears x this movement of the shaft g may be varied. On one end of the shaft g , outside of the frame, is a disk z , and a horizontal lever 1 is supported close to the side of this disk z , on which lever is a cam 2 , which is offset from the side of the lever toward said disk sufficiently to permit the engagement with the edge thereof of a roller-stud 3 . One end of this lever 1 is supported on a stud on the frame and slides thereon. This stud has no other function than to support the cam 2 in proper position relative to the disk z . The opposite end of the lever 1 is pivotally con-

nected with the lower end of a vertically-operating lever 4 , the upper end of which is connected by a short adjustable connection 5 with the lower arm 6 of a bell-crank lever 7 , to whose upper arm 8 is connected the bar 9 , which extends along the front of the cylinder j and is pivotally connected to each of the arms r thereof. It is thus apparent that the rotation of the disk z in the direction shown by the arrow will not be effective to move the lever 1 until the roller-stud 3 arrives at a point on the cam 2 where the curved line of that cam begins to run eccentrically to the disk z . The movement of the stud will be ineffectual to impart horizontal movement to the lever. After the engagement of the edge of the cam with the stud 3 said cam will be forced in a horizontal direction far enough to permit the said stud to pass under the point of the cam. This will bring the lower curved edge of the cam to a position about diagonally opposite the position it occupies in Fig. 1—that is, with the lower curved edge of the cam concentric with the disk z . The cam thus provides a period of dwell for each half-revolution of the disk z , and it is during one of these periods that mixture is drawn into the cylinder on the upstroke and during the other of said periods is forced out of the cylinders. Each oscillatory movement of the cylinders closes the outlet and opens the inlet of the cylinders, and vice versa.

Whatever may be the stroke of the piston there need never be any variation in the oscillatory throw of the cylinders. Therefore no means of adjustment are provided in the mechanism above described; but as on certain classes of goods it is possible to run the machine at a higher speed than on others means are provided for varying the speed of rotation of the shaft g , which will now be described.

On the shaft h are three gears x , having different diameters. An intermediate gear v is hung between the forked ends 10 of an arm 11 , (see Figs. 1 and 2,) which arm is supported at one end on a stud 12 in an arm 13 , which in turn is supported on the brace-rods 14 , extending from one side of the frame to the other. The opposite ends of the arm 11 —that is, the ends of the forks 10 —are supported on the shaft g and embrace between them the large gear u .

Of the above mechanism only the group of gears x is immovably fixed, and these are, as stated, on the shaft h . The arm 11 , whose forked ends embrace the gears u and v , is movable with said gears on the shaft g and on the brace-rod 14 , the gear u having a spline-and-groove connection with the shaft g , and the arm 13 , to which the lower end of the arm 11 is connected, has a similar sliding movement on the rod 14 , the said arm 13 being provided with a set-screw for locking it in its position. Obviously as the intermediate gear v must mesh with gears of varying diameters

on the same shaft it is necessary to provide vertical movement for the arm 11, and to this end the end of said arm which is secured to the arm 13 is turned downward at an angle to the main dimension of the arm and has a slot 15 cut therein, which is substantially concentric with the shaft *g*, the stud 12 passing through this slot. To change the speed of the shaft *g*, it is therefore only necessary to loosen the set-screw which binds the arm 13 to the rod 14 and then to move the arm 11 until the intermediate gear *v* lies directly over the gear with which it is desired to make it engage. The nut on the stud 12 is then loosened and the arm dropped down until the gear *v* meshes with the desired one of the gears *x* on the shaft *h*. The nut on the stud 12 is then tightened.

The means for imparting the requisite vertical movement to the piston-bar 16 are provided by two eccentrics 17 on the shaft *g*, the arms of the eccentrics, as shown in Fig. 2, being extended upward and pivotally connected with swinging yokes 18 on each side of the machine, secured by one end on a rod 19, on which they may swing. In these yokes the lower extremities of the connecting-rod 20 are pivotally supported, and the upper extremities thereof are pivotally connected to opposite ends of the piston-bar 16, which has thereby a vertical sliding movement on the face of the tank, supported in any convenient manner. The pivotal connection of the lower end of said connecting-rod 20 consists of a block, which has a sliding motion in a slot 21, which is concentric with the point of attachment of the connecting-rod 20 and said piston-bar. A long screw 22 passes through the rod 19 and through said block on which the connecting-rod 20 is supported and with which it has a screw engagement. A hand-wheel is applied to the end of one of the screws 22, and a small sprocket-wheel 23 is fixed on each of said screws also. A sprocket-chain 24 runs over both of said sprocket-wheels. By means of this construction by rotating said hand-wheel on one of said screws both screws are simultaneously rotated, and the position of the block in the slot 21, with which the connecting-rod 20 is engaged, may be moved farther away from or nearer to the rod 19, on which the yoke 18 oscillates, whereby the throw of the piston-bar vertically may be regulated at will. The throw of the eccentrics 17 remains constant.

The pistons *s* may be connected with the piston-bar 16 in any suitable manner. It has been thought best in this application to make a T-head slot 25 in the under side of the piston-bar 16 from one end thereof to the other and to introduce therein from one end the piston-rod 26, provided with cylindrical heads adapted to enter said slot, these piston-rods being screwed into the pistons *s* in the usual manner.

From the preceding description of this machine it is obvious that upon each upstroke

of the piston the latter will draw into the cylinder a certain amount of confectionery material from the tank *i* in proportion to the stroke of said piston and upon the descent of said piston (the cylinders meanwhile having been rotated to bring the proper outlet-ports into registering position) the contents of the cylinders will be forced through the coinciding holes *q* and *o* and deposit the same in four mold-forms *t* or into whatever number of mold-forms the machine may be adapted to. It will be observed by a glance at Figs. 3 and 4 that the deposit of material in said forms is made in two molds lying side by side in two parallel rows extending transversely of the trays *e*. A ratchet-motion, before referred to and shown in Figs. 1, 2, and 5, is operated from a crank-arm 27. (Shown in Fig. 5 and in dotted lines in Fig. 1 on the shaft *g* and also shown in Fig. 2 on the right-hand end of said shaft.) From the free end of this crank-arm 27 three connecting-rods 28, 29, and 30 extend, respectively, to three swinging levers 31, 32, and 33, all of which swing freely on the shaft *d* outside of the frame *a*, as shown in Fig. 2. Each of these swinging levers carries a pawl. The pawl 34 on the arm 33 is the one which determines the extent of movement of the tray between each step, except as follows, by means of its engagement with the teeth of a ratchet-wheel 35, which is fixed on the end of the shaft *e*.

The transverse rows of mold-forms impressed in the starch in the trays *e* are equally spaced one relative to the other, and the first and last rows are each the same distance from the ends of the trays; but where two trays come together, as they do in following one another in close contact through the machine, the space between the last row of one tray and the first row of another is greater than the space between said rows, and consequently it is necessary to provide for a given number of steps of a given length for each tray and then one step of a greater length to bring the first row or rows of the mold impression under the openings in the bottom of the cylinder-bar, and it is to provide for this unequal feed movement for the trays that the ratchet motion has been devised. This device, however, forms the subject of a separate application and will only be described herein in its relation to this particular machine.

The intermittent motion of the ratchet referred to is provided for by means of the pawl 36 on the swinging lever 32, which is permitted to come into engagement with the ratchet-wheel 35 periodically at the same time that the pawl 34 comes into engagement behind it after having brought the last row of mold-forms under the cylinders of the machine. There is attached to the axis of the pawl 36 a finger 37, the end of which bears on the periphery of a cam 38, to which is secured a ratchet-wheel 39, having as many teeth as there are steps to be made by the

tray to fill all of the mold-forms therein. The said cam and the ratchet are loose on the shaft d , and the ratchet is engaged by a pawl 40 on the upper end of the swinging lever 31, 5 said cam being of such a form that at the completion of each revolution of said ratchet-wheel 39 the finger 37 will drop off from a shoulder on said cam, and thus permit the pawl 36 to come into engagement with the 10 teeth of the ratchet-wheel 35. Now it will be observed that the same crank 27 imparts to the levers 32 and 33 their swinging motions, but that said levers are provided with long slots 41 and that the connecting-rods 29 and 15 30, extending from said crank to said arm, are attached to the latter at different distances from the shaft d . Consequently the lever 32 being swung from a point nearer the shaft d than the lever 33 will carry its 20 pawl farther than will the latter. Thus by means of the cam referred to the pawl 36 when it is allowed to drop onto the ratchet-wheel at the beginning of the stroke of the pawl 34 after the last row in a tray has been 25 filled will by reason of its longer stroke carry the ratchet-wheel 35 a certain distance after the pawl 34 has reached the limit of its movement. It is thus apparent that by varying the number of teeth of the ratchet-wheel 39 30 to agree with the number of steps that a tray must make to fill its rows of mold-forms and by varying the point of attachment of the connections 29 and 30 with the levers 32 and 33 the machine may be adapted to operate on 35 trays having molds printed very closely together and having more or less variation in the distance between the last row of molds in one tray and the first row in the next succeeding tray. This ratchet-feed is a very important feature of this construction, for a continuous feed for the trays is thereby made possible, whereas heretofore the trays have been placed separately on the conveyer-chain and its first row of mold forms brought into proper 40 position under the discharge-openings of the cylinders.

In Figs. 6 and 7 of the drawings there is shown a modification of the construction heretofore described whereby the deposit of confectionery material may be made in more than one mold at a time and which it is thought comes within the scope of the invention. The essential difference between this modified construction and that previously described 55 consists in providing the cylinder-bar with two rows of cylinders adapted to deliver material into the molds of two contiguous rows of molds simultaneously, each cylinder, however, having but one opening, instead of delivering the material into said two rows from cylinders having a plurality of openings, as heretofore described.

In carrying out this invention the cylinder-bar k , instead of being supported on the lower 65 front edge of the tank, is supported on an intermediate piece 42, secured to the under side

of the tank near its front edge and provided with the delivery-slot n , which in this case is nearly vertical. The said cylinder-bar k , properly secured to the lower edge of this 70 piece 42, projects rearwardly far enough to permit the location in the rear edge thereof of a series of horizontal cylinders 43, the cylinders j , as in Fig. 3, being supported in a perpendicular position. The said cylinders 75 43 and j are in communication with the slot n through the passages 44 and 45 in the cylinder-bar, and each cylinder is provided with a suitable inlet-port 46 and discharge-port 47. Proper discharge-ports in the bottom of the 80 cylinder-bars are provided which register with the ports 47 at the proper time. The cylinders j and 43 also are adapted to have an oscillatory motion on their axes at the same time, and their pistons s and 48 also have simultaneous inward and outward strokes. These simultaneous movements of the cylinders j and 43 are provided for, as shown in Fig. 7, by extending an arm 49 from the axis of the lever 4 and connecting said arm by a 85 rod 50 with one end of an elbow-lever 51, the opposite end of which is connected to a bar 52, with which arms on the cylinders 43 similar to the arms r on the cylinder j are pivotally connected. The cam 2 thus operates 90 both sets of cylinders. The pistons of these cylinders are also operated from the same source by taking a connecting-rod 53 from the pivotal support of the rod 20 in the yoke 18 and extending it upward to one arm 54 of an 95 elbow-lever suitably supported in the machine, the opposite arm of which engages with the piston-bar 55, which has a horizontal sliding motion in suitable supports 56 on the frame of the machine. It will be of course 100 understood that the connecting-rod 53 and the arm 54 are located one on each side of the machine, as is the case with the connecting-rod 20.

Having thus described my invention, what I claim, and desire to secure by Letters Patent of the United States, is—

1. The combination with the supply-tank of a confectionery-depositing machine, of a cylinder and its piston, supported in proximity thereto, an inlet-port in said cylinder in communication with said tank, one or more outlet-ports in the cylinder, and means for rotating said cylinder, whereby said inlet and outlet ports may be alternately opened and closed in operative relation to the movements of said piston, and means for moving the latter, substantially as described.

2. The combination with the supply-tank of a confectionery-machine, of a cylinder and its piston, supported in proximity thereto, an inlet-port and a plurality of outlet-ports in said cylinder, means for alternately opening and closing said inlet and outlet ports in operative relation to the movements of the piston, whereby, upon one stroke of the latter, the cylinder may be filled with material from

the tank, and upon the opposite stroke discharge said material through said outlet-ports, substantially as described.

3. A depositing-machine for confectionery mixtures comprising a supply-tank, a series of trays, molds formed in suitable material therein, ratchet mechanism for moving said trays through the machine with a uniform step-by-step movement, and means for changing the length of one of said ratchet steps at predetermined intervals, substantially as described.

4. A depositing-machine for confectionery mixtures comprising a supply-tank, a series of trays, molds formed in rows in suitable material therein, mechanism for moving a series of said trays end to end through the machine automatically, with a continuously forward movement and means for depositing confectionery material in one or more of said rows simultaneously, substantially as described.

5. A depositing-machine for confectionery mixtures comprising a supply-tank, a series of trays, molds formed in rows in suitable material therein, mechanism for moving a series of said trays end to end through the machine automatically, a series of cylinders supported in proximity to said tank, pistons in said cylinders, a port in each of the latter communicating with said tank, a plurality of discharge-outlets from said cylinders, and means for alternately opening and closing said inlet and discharge outlets by the oscillation of said cylinders, substantially as described.

35 6. In a depositing-machine for confectionery mixtures, a supply-tank, a series of cylinders supported in proximity to the latter, an inlet-port and a plurality of discharge-ports in said cylinders, a piston-bar, pistons supported therein and entering said cylinders, and means for reciprocally and adjustably operating said bar in line with the axis of said cylinders, consisting of a swinging yoke,

connecting-rods between said yoke and said bar, an eccentric for operating said yoke, and means on the latter for shifting the point of connection of said connecting-rods therewith, substantially as described.

7. In a confectionery-depositing machine, the combination with a supply-tank, of a cylinder-bar supported thereon, a cylinder in said bar, a piston, an inlet and one or more outlets in said cylinder, and means for oscillating the latter, whereby when said inlet is thereby closed said outlet will be opened and vice versa, together with means for operating said piston, substantially as described.

8. In a confectionery-depositing machine, the combination with a supply-tank, of a piston-bar supported thereon consisting of a solid piece having a series of cylinder-receiving sockets formed therein, cylinders fitted in said sockets for axial rotation therein, an inlet-port in said cylinders communicating with said tank, one or more outlet-ports extending through the lower part of said cylinder and through said bar, and means for rotating said cylinders at the proper time to open and close said outlet and inlet ports alternately, substantially as described.

9. In a machine of the class described, a tray having molds formed in suitable material therein in uniform rows, a supply-tank, a mold-charging cylinder in communication with said tank and adapted to discharge confectionery mixture into said molds in two or more rows simultaneously, and means for moving said trays through the machine with an intermittent movement consisting of a series of uniform steps, periodically interrupted by a step or steps of different length, substantially as described.

GABRIEL CARLSON.
